United States Patent Office.

PATRICK FRANCIS MILLIGAN, OF WASHINGTON, DISTRICT OF COLUMBIA.

Letters Patent No. 63,649, dated April 9, 1867.

CHECK ON CAR CONDUCTORS.

The Schedule referred to in these Letters Patent and making part of the same.

TO ALL WHOM IT MAY CONCERN:

Be it known that I, PATRICK FRANCIS MILLIGAN, of Washington, in the county of Washington, and District of Columbia, have invented a new and improved Mode of Preventing the Conductors on City Passenger and other Railroad Cars from Defrauding the Companies; and I do hereby declare that the following is a full, clear, and exact description thereof, reference being had to the accompanying drawings, and to the letters of reference marked thereon.

The nature of my invention consists in providing each conductor with a certain number of checks for each day, on which will be printed the name of the company, the day of the week, the day of the month, and the year, as also the amount of fare charged, one of which he will be bound to give to each passenger when he collects the fare, piercing it at the same time, which the passenger, on leaving, will drop into a check-box prepared to receive it at each end of the car, the keys to which will be held by some responsible officer of the company. The amount of money and balance of checks handed in by each conductor at the end of each day's work must balance with the number of checks which he received in the morning, each check being equal to six cents.

To enable others skilled in the art to make and use my invention, I will proceed to describe its construction and operation.

At each end of the car, on the right-hand side going out, I construct a rectangular box, B, ten inches by twelve, and six inches deep, placed under the seat, and open in front, being fastened to the floor or end of the car. I construct a drawer, D, which slides into this box, and is locked by a drawer-lock or padlock, or both. In the top of this box, and over the drawer, I make an aperture of say one inch, and I insert tightly therein a tube, b, of brass, iron, or tin, and having a branch tube, a, leading from it to the platform of the car, both having a funnel mouth, as seen at fig. 1 in the accompanying drawings, which is an inside view through the car, showing the position of the check-box under the seat. These tubes are so placed that passengers can easily drop their checks. I have checks of a proper size printed on strong paper, in sheets of any number, bearing the name of the company, the day of the week, the day of the month, and the year, as also the amount of the fare charged, (as, Washington and Georgetown Railroad Company, Wednesday, March 6, 1867, fare six cents,) as seen at fig. 2, c being the check. The conductor will be bound to give one of these checks to each passenger when he collects the fare, piercing it at the same time, which will protect the passenger from being called on twice for fare, and which he will drop into the check-box on leaving the car. I will place in conspicuous places cards, notifying the passengers of the duty of the conductors, and their own, as also the number of each car, so as to enable passengers to report any negligence on the part of conductors. In case of the application of this invention to railroad trains drawn by locomotives, the checks should be marked for the amount of way-stations, and the branch tube a need not be in use, and the box can be arranged in any manner as best suits the convenience of the company. In and under all circumstances the same principle, however, is carried out. Now, as to city passenger railroad cars, say that a conductor receives in the morning five hundred checks, and that he pays out four hundred and fifty to passengers, then he will have fifty checks and twenty-seven dollars to hand in at night, suppose the fare to be at six cents. But suppose that he fails to give twenty passengers their checks, then he would have twenty persons cognizant of his theft, for one dollar and twenty cents, whose duty it was to demand their checks, any one of whom might inform on him. A small reward, say five dollars, would lead to the detection of all such conduct, and the prompt discharge of such a conductor would prevent a repetition of it. It will be seen that if a passenger steps off the car without dropping his or her check into the check-box, that it does not enable the conductor to hold that amount for his own use unless he can tell the exact number of persons so doing, and furnishing forged checks to make up the number, which would be almost impossible, as the company could baffle all attempts at procuring forged checks, by private marks, and allowing none but the president's signature in ordering checks from the printers. Forged checks could also be used by abstracting the checks from the check-box by means of false keys, and adding forged checks for the number. But in procuring such keys the difficulty would be great, and, besides, the company could have the cars visited as often as necessary in the course of the day, and the checks taken out and placed to the credit of the car until night; besides, there are passengers in the cars to notice and report such proceedings. Further, by adding to the amount of money received the amount of checks on hand, the president could see that the amount was equal to

the number of checks furnished by him in any given time, and thereby prevent fraud by any other officer of the company. The check-boxes may be of cast iron, and vary in dimensions to suit circumstances. The drawers can be drawn out and the checks removed more easily than if it were a box without a drawer, which might answer under some circumstances on trains drawn by locomotives. I do not claim the use of checks when used for any other purpose whatever, as a part of my invention, but what I do claim, and desire to secure by Letters Patent, is—The employment, in a car or other similar vehicle, of the checks or tickets C, check-box B, drawer D, and tubes a b, when constructed and arranged substantially as and for the purpose specified. PATRICK FRANCIS MILLIGAN.
